(57) **CLAIM**

The ornamental design for a heat moldable orthotic insert, as shown.

DESCRIPTION

FIG. 1 is a perspective view of a heat moldable orthotic insert showing our new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.
